CLAIM

The ornamental design for a game board, as shown and described herein.

DESCRIPTION

FIG. 1 is a side elevational view of a game board showing our new design; shown in it's environmental use; FIG. 2 is an enlarged scale side elevational view thereof; FIG. 3 is a front elevational view thereof;

FIG. 4 is a top plan view thereof;

FIG. 5 is a rear elevational view thereof; and,

FIG. 6 is a bottom plan view thereof.

The broken lines showing of bowling alley in FIG. 1 and the net in FIG. 3 are for illustrative purpose only and forms no part of the claim. The views in FIG 2 through 6 are shown in enlarged scale for clarity.

1 Claim, 3 Drawing Sheets

FIG. 1

FIG. 2

FIG. 3

FIG. 4

FIG. 5

FIG. 6

UNITED STATES PATENT AND TRADEMARK OFFICE
CERTIFICATE OF CORRECTION
